MESNE ASSIGNMENTS, TO LEONARD L. ELDEN, OF BROOKLINE, MASSACHUSETTS,
AND DAVIS S. BOYDEN, OF BOSTON, MASSACHUSETTS.

OVERLOAD-INDICATING APPARATUS FOR TRANSFORMERS.

Application filed August 15, 1922. Serial No. 582,057.

To all whom it may concern:

Be it known that I, THOMAS DONALD ADAIR, Jr., a citizen of the United States, residing at Dorchester, in the county of Suffolk and State of Massachusetts, have invented certain new and useful Improvements in Overload-Indicating Apparatus for Transformers; and I do hereby declare the following to be a full, clear, and exact 10 description of the invention, such as will enable others skilled in the art to which it appertains to make and use the same.

The present invention relates to an improvement in overload indicating apparatus for transformers, and more particularly to semaphores for use in connection with such apparatus.

In the transformer disclosed in the application filed by T. Donald Adair, Jr., April 20, 1921, Serial No. 459,574, the semaphore was enclosed within a semaphore box having a window in one side. With such construction when the semaphore drops it is exhibited at the window. In practice, in 25 order to render the semaphore visible and distinguishable, it is painted white. Upon the occurrence of transformer overload the white semaphore was exposed to view by the dropping behind the window. The box, 30 however, was made of metal and the inside was illuminated only by such light as could enter through the window, as a consequence of which there was a mirror effect observed. The glass in certain positions of the sun or 35 clouds would reflect light to such an extent that the observer at a distance, as was necessary because the transformers are usually mounted on poles, would be unable to distinguish the light reflected from the 40 glass from the white semaphore.

It was attempted to overcome this objection by the construction disclosed in the application of T. Donald Adair, Jr., filed October 11, 1921, Serial No. 507,029, by providing the box with two windows, one at 45 each side, so that transmitted light might be availed of, that is to say, light passing clear through the box, to indicate the falling of the semaphore when it stood against a light background, and at the same time it was provided that a white screen covering part of the area between the two windows should be exposed by the dropping of

the semaphore for the purpose of rendering the signal visible against a dark background. But the box in this case, as in the former, was made of metal and excluded light more or less, and consequently in this box, as in the former, the mirror effect was still encountered, and under some conditions it interfered with the visibility of the signal.

The value of these semaphores is considerable even if the visibility of the signal is low, but with a high visibility the value 65 of the signal is much enhanced. To this end the present invention contemplates the production of a signal of high visibility, and consists in the semaphore hereinafter described and particularly defined in the 70 claims.

In the accompanying drawings illustrating the preferred form of the invention, Fig. 1 is a vertical sectional elevation of the 75 construction of the invention; Fig. 2 is a transverse sectional elevation; and Fig. 3 is a plan.

The illustrated embodiment of the invention is described as follows: The overload indicating apparatus for transformers comprises a semaphore 19 operated by mechanism responsive to the overload conditions of the transformer coils, comprising a heat responsive element, such as a coil or spiral like that described in said applications, or 80 of any suitable form, which is connected 85 to a rotatable spindle 25 journaled at its upper end in a cross bar 27 within the semaphore box 28, mounted on the upper end of a depending boss 29, having a threaded 90 portion 30 adapted to be screwed into a hole in the cover of the transformer. Variations in the temperature of the coils in the 95 transformer operate through the expansion or contraction of the heat responsive coil or spiral to cause rotation of the rotatable 100 spindle 25. The semaphore box 28 is made of one piece of glass. It is provided with bail groove projections 31 on its top which receive the horizontal portion of the bail 105 32 which has two arms extending downward at the sides of the box which enter two slots 33 in the base plate 34 and receive on their ends the knurled nuts 35. A rubber washer 36 is interposed between the base plate 34 and the lower edge of the

box 28. By screwing up the nuts on the bail the box is clamped tightly against the base plate, and the entrance of water or air through such opening is prevented. The 5 semaphore 19 is supported to slide on vertical rods 40 and is normally held in raised position and permitted to fall when the temperature of the oil in the bath reaches a point corresponding to warning or over-load condition. The semaphore is supported in its raised position by a leaf spring 41, secured at its upper end to the semaphore, and having its lower end resting upon the upper surface of a horizontal segmental disk 15 42 secured to the upper end of the rotatable spindle 25. This disk 42 is provided with a notch through which the supporting spring 41 is permitted to pass when the disk is rotated to bring the notch under the spring, 20 as in the construction of said applications. This spring 41 is permitted to fall by two steps, being provided with a shoulder 43 which, when the semaphore is first permitted to fall, catches on the disk 42 and holds 25 the semaphore in a position half-way between its top and bottom positions. This construction is like that illustrated in the Davis S. Boyden application filed June 16, 1921, Serial No. 478,205.

30 The semaphore is provided with a re-setting device consisting of a lever 44 pivoted at 45, adapted to be engaged on its under side by the re-setting pin 46. The re-setting pin projects through the bottom of the 35 base of the device and is covered by a cap 47 which has a hole extending downward in its center for a distance to receive the lower end of the re-setting pin and which has a screw-threaded shank adapted to be received in a screw-threaded hole in the base, through which the re-setting pin, much 40 smaller in size, projects. A rubber washer 48 interposed between the head of the cap 47 and the bottom of the base plate enables 45 the closure to be made tight. By means of the washer under the box and the washer under the resetting pin cap the apparatus is made hermetically tight, and this prevents 50 the entrance and egress of air and of moisture, and maintains the condition of the apparatus free from exposure to the influence of the weather and insects.

The upper ends of the two rods 40 are received in two holes in the top piece 49 of a 55 frame, which as seen in Fig. 2, consists of a flat base 27 and two vertical supports 50 (see Fig. 1), upon the upper ends of which the horizontal top piece 49 is formed. This frame is secured to the two posts 51 and 52 60 (of which the post 51 carries the resetting lever) which are formed on the base plate 34.

Irrespective of the surroundings or the background against which this device may be viewed, the full light which is enabled 65 to illuminate the whole apparatus by reason

of the box being made of glass, substantially completely obviates any mirror effect on the glass. When it is viewed against a dark background the semaphore cuts off that dark background. When it is viewed against a light background, the semaphore presents a dark object against it. The result is that the semaphore is one of high visibility by reason of the employment of a glass box or cover. The ideal condition would, of course, be that in which no cover at all was employed, but such condition is, as a matter of practice, impossible because weather conditions and the liability of injury by animals such as birds, squirrels and insects would be present, so that the present construction offers an approximation to such ideal conditions which secures a high degree of visibility of the semaphore. 75 80 85

The use of the bail construction for holding the box on the base plate is of great convenience in the use of the device because it enables the inspector to remove the cover entirely and to have full and free access to the apparatus for the purpose of cleaning it, for removing any rust, dust, corrosion or other impediments to its good operation, and quickly to restore it to its original tight condition at each cleaning operation. 90 95 100

The feature of hermetically sealing the box is one which contributes greatly to the life and durability of the instrument because it prevents the corrosion and deterioration incident to the change of the air content of the box due to the expansion and contraction of such air resulting from changes of temperature. 105 110 115

It will be observed that it is essential that the front and back walls of the casing shall be transparent and that the semaphore-plate 19 shall not only be substantially opaque but shall have substantial width, so that when it is in its up position it will, so to speak, block off a large part of the top panel of the casing, leaving the lower half or panel substantially transparent to enable the light rays to pass clear through the casing. When the opaque semaphore-plate is down, then the conditions are reversed, the light passing clear through the top zone or panel of the casing. In this way, the panel blockaded off by the opaque plate will, by comparison with the transparent section of the casing, be readily observable at a considerable distance and under all conditions of 120 125 130

Having thus described the invention, what is claimed is:

1. Overload indicating apparatus for transformers having, in combination, a 125 semaphore, a heat sensitive element, connections between the semaphore and the heat sensitive element permitting the semaphore to drop upon the indication of critical temperature by the heat sensitive element, a box 130

for covering the semaphore, a wire bail extending over the box, and means for securing it to the base plate to hold the box in place thereon.

5 2. Overload indicating apparatus for transformers comprising a heat sensitive element, a semaphore, connections between the heat sensitive element and the semaphore acting to drop the semaphore upon the attainment of a critical temperature at the heat sensitive element, a base plate for supporting the semaphore, a box for covering the semaphore, means for packing the joint between the box and the base plate, a re-setting device having a portion extending through the base plate, and a cap for cover-

ing the re-setting device, said box and cap hermetically closing access to the box.

3. An overload indicating apparatus for transformers having, in combination, a box 20 for enclosing the indicating apparatus, the walls of this box being transparent, said indicating apparatus embodying a light-obstructing semaphore-plate of substantial width adapted to be held in the upper part 25 of the casing or in the lower part thereof, so that in either position it will render the casing nontransparent at that point and thus indicate at a glance under all light conditions whether the semaphore-plate be up 30 or down.

T. DONALD ADAIR, JR.
